CLAIM

The ornamental design for an electric clipper, as shown and described.

DESCRIPTION

FIG. 1 is a top, front, left perspective view of an electric clipper, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top, front, left perspective view of detail “8” identified in FIG. 1, shown enlarged for clarity of disclosure. The broken lines in the drawings illustrate the portions of the electric clipper, which form no part of the claimed design. In the drawings, the equal-length broken lines depict portions of the electric clipper and form no part of the claimed design.

1 Claim, 8 Drawing Sheets
